OBLIQUE RAIL JOINT

George A. Standfast, Jefferson City, Mo.

Application December 15, 1950, Serial No. 200,975

3 Claims. (Cl. 238—230)

1

This invention relates to oblique or scarf rail joints and constitutes an improvement on the rail joint disclosed in my Patent No. 2,472,446, issued June 7, 1949.

It is among the objects of the present invention to provide an improved oblique rail joint which is simple in construction and economical to manufacture, which uses the same kind of coupling plates or fish plates and the same number of connecting bolts as the conventional butt joint; which does not weaken the rail at its ends; which provides a somewhat longer joint than that disclosed in my prior patent to provide a smoother path for wheels thereon; and which includes means for maintaining the end portions of adjacent rails in accurate alignment under conditions of heat expansion of the rails and wheel loads thereon so that the oblique rail ends are not offset relative to each other by such expansion and loads and the acute ends of the rail are not broken or distorted, no shock or deflection is imparted to the car wheels traveling over the joint and no excessive strain is placed on the connecting plates and bolts.

Other objects and advantages will become apparent from a consideration of the following description and the appended claims in conjunction with the accompanying drawing wherein:

Figure 1 is a fragmentary perspective view of two rail end portions interconnected by an oblique rail joint illustrative of the invention;

Figure 2 is a side elevational view of the rail end portions and joint illustrated in Figure 1;

Figure 3 is a top plan view of the rail end portions and oblique rail joint illustrated in Figures 1 and 2; and

Figure 4 is a diagonal cross sectional view on the line 4—4 of Figure 3.

With continued reference to the drawing, there is illustrated in Figure 1 abutting end portions 10 and 11 of two interconnected railroad rails with a diagonal rail joint between such abutting ends. It is to be understood that a similar joint is provided between each pair of abutting rail ends and that each rail has on its opposite ends the same formation inclined in the same direction so that either end of one rail may be connected in the same manner to either end of an adjacent rail, there being no predetermined end to end relationship of the rails.

The rail 10 has a base flange 12, a rail head 13 provided with rounded edges and a web 14 disposed between and interconnecting the flange and the rail head. The rail head tapers somewhat in thickness in a direction away from the

2

web 14. The rail 11 has a corresponding flange 15, rail head 16 and web 17 interconnecting the flange 15 and head 16.

The rail end 10 is obliquely or diagonally cut off on two planes, as indicated at 18 and 19 which planes are both perpendicular to the bottom surface of the rail flange 12 and are spaced apart and substantially parallel to each other. The two cuts thus provided extend from respectively 10 opposite sides of the rail substantially to a plane which is perpendicular to the bottom surface of the rail flange and includes the longitudinal center line of the rail, and a cut in a third plane 20 interconnects the cuts on the planes 18 and 19 at the center of the rail. The third plane 20 is also substantially perpendicular to the bottom surface of the rail flange and intersects the planes 18 and 19 substantially perpendicularly at respectively opposite sides of the plane including the center line of the rail.

The distance between the two parallel planes 18 and 19 and consequently the width of the plane 20 of the intermediate cut, is preferably not greater than one-eighth of an inch and for light rails may be of the order of one-sixteenth of an inch and the planes 18 and 19 are both disposed at an angle of less than 45° to the plane perpendicular to the bottom surface of the rail flange and including the longitudinal center line of the rail, an angle between the two planes on which the rail end is cut and a plane perpendicular to the bottom surface of the rail flange and including the longitudinal center line of the rail of approximately 30° being preferred.

The entire rail end formation may be conveniently provided by cutting the rail from opposite sides with band saws or reciprocating saws. One saw will be used to cut diagonally half way across the rail with its side adjacent the length of the rail on the plane 19 and the other saw will be used to cut diagonally from the other side of the rail to the center of the rail with its side adjacent the length of the rail on the plane 18. The plane 20 will thus have a width equal to the thickness of the first mentioned saw and a saw of suitable thickness will be selected for this cut. The thickness of the saw cutting along the plane 18 is immaterial so long as it has sufficient structural strength.

The tips of acute ends of the flanges 12 and 15 are cut off, as indicated at 21 and 22, to remove the sharp corners from the rail ends and avoid danger of personal injury to workmen laying the rails, and the acute ends of the rail heads are dressed off, as indicated at 31 and 32,

so that no extremely thin portion is present to be bent or broken by the flanges of wheels passing over the rails as explained in my Patent No. 2,472,446 referred to above.

When two rail ends are brought together in the manner indicated in the drawing, the cuts on the corresponding planes 20 provide overlapping jogs or shoulders at the mid-width location of the interconnected rails extending from the bottom surface of the rail flanges to the top surface of the rail heads. The cut extending from the side of the rail at the acute end thereof to the shoulder is disposed inwardly longitudinally of the rail of the cut extending from the other side of the rail to the shoulder so that the surface of the shoulder faces the acute end or point of the rail. When the adjacent ends of two rails disposed in end to end relationship are brought together the shoulders 20 are mutually opposed in a direction to prevent the diagonal surfaces of the rail ends from sliding past each other upon elongation of the rails and this keeps the acute or tip ends 23 and 24 of the rail heads of the two interconnected rails in alignment with the side surfaces of the rail heads so that these acute ends are not forced outwardly and damaged by the flanges of car wheels passing over the rails. Even when the rails are subjected to high heat expansion or excessive loads, the overlapping shoulders cooperating with the diagonal cuts maintain the interconnected rails in perfect longitudinal alignment and preclude any relative lateral displacement of the two rail ends at the rail joint.

The web 14 is provided near the rail end with two bolt holes spaced apart longitudinally of the rail and the web 17 is provided with two similarly located bolt holes and fish plates 25 and 26 of well known form, are placed one at each side of the interconnected rail webs and each fish plate overlaps the webs of the two rails adjacent the rail joint. These fish plates are provided with holes registering with the holes in the webs 14 and 17 and tie bolts 27 are inserted through the holes in the fish plates and the webs. Nuts 28 are threaded onto the screw threaded end portions of these tie bolts to firmly clamp the fish plates against the corresponding sides of the rail webs and the fish plates and bolts hold the rail ends together at the joint. The overlapping shoulders at the center of the rail together with the diagonal cuts at the rail ends, by holding the rail ends against relative lateral displacement, eliminate any excessive strain on the fish plates 25 and 26 and the bolts 27, the loads on the fish plates being mainly in tension and the loads on the bolts mainly in shear.

The joint formation on each rail end can thus be provided by a single, simple sawing operation, providing maximum economy, and is effective to hold the rail ends in alignment against relative lateral displacement, to protect the acute ends of the diagonally cut rail heads and to relieve the rail connecting fish plates and bolts from excessive strain. The diagonal or oblique joint, having an angle to the longitudinal center plane of the rails less than 45°, is of adequate length to provide a smooth path of travel for the car wheels from one rail to the connected rail so that the car wheels will not bump at the rail joints.

The invention may be embodied in other specific forms without departing from the spirit or essential characteristics thereof. The present embodiment is, therefore, to be considered in all

respects as illustrative and not restrictive, the scope of the invention being indicated by the appended claims rather than by the foregoing description, and all changes which come within the meaning and range of equivalency of the claims are, therefore, intended to be embraced therein.

Having thus described the invention, what is claimed is:

1. In railway rails each having a flange, a web and a head, an oblique rail joint between the adjacent ends of rails disposed in end to end relationship comprising diagonal surfaces on each rail end disposed in spaced apart and substantially parallel planes perpendicular to the bottom surface of the corresponding flange and extending one from the side of the rail at the acute end thereof to a location adjacent a plane perpendicular to the bottom surface of said flange and including the longitudinal center line of the rail and the other from a location adjacent the last mentioned plane to the other side of the rail, said other surface being disposed outwardly of said one surface longitudinally of said rail and there being a third surface extending between the ends of the two above mentioned surfaces adjacent said last mentioned plane and disposed in a plane perpendicular to the bottom surface of said flange and to said parallel plane, said third surface providing a shoulder extending from the bottom to the top of the rail and facing the acute end thereof, the diagonal surfaces of said adjacent rail ends being disposed in face to face relationship and said shoulders being mutually opposed in a direction to preclude sliding of said diagonal surfaces past each other when said rails are subject to elongation.

2. In railway rails each having a flange, a web and a head, an oblique rail joint between the adjacent ends of rails disposed in end to end relationship comprising diagonal surfaces on each rail end disposed in spaced apart and substantially parallel planes perpendicular to the bottom surface of the corresponding flange and extending one from the side of the rail at the acute end thereof to a location adjacent a plane perpendicular to the bottom surface of said flange and including the longitudinal center line of the rail and the other from a location adjacent the last mentioned plane to the other side of the rail, said other surface being disposed outwardly of said one surface longitudinally of said rail and there being a third surface extending between the ends of the two above mentioned surfaces adjacent said last mentioned plane and disposed in a plane perpendicular to the bottom surface of said flange and to said parallel plane, said third surface providing a shoulder extending from the bottom to the top of the rail and facing the acute end thereof, the diagonal surfaces of said adjacent rail ends being disposed in face to face relationship and said shoulders being mutually opposed in a direction to preclude sliding of said diagonal surfaces past each other when said rails are subject to elongation, said parallel planes being disposed at an angle of less than 45° to said plane including the longitudinal center line of the rail.

3. In railway rails each having a flange, a web and a head, an oblique rail joint between the adjacent ends of rails disposed in end to end relationship comprising diagonal surfaces on each rail end disposed in spaced apart and substantially parallel planes perpendicular to the bottom surface of the corresponding flange and ex-

tending one from the side of the rail at the acute end thereof to a location adjacent a plane perpendicular to the bottom surface of said flange and including the longitudinal center line of the rail and the other from a location adjacent the last mentioned plane to the other side of the rail, said other surface being disposed outwardly of said one surface longitudinally of said rail and there being a third surface extending between the ends of the two above mentioned surfaces adjacent said last mentioned plane and disposed in a plane perpendicular to the bottom surface of said flange and to said parallel plane, said third surface providing a shoulder extending from the bottom to the top of the rail and facing the acute end thereof, the diagonal surfaces of said adjacent rail ends being disposed in face to

10

face relationship and said shoulders being mutually opposed in a direction to preclude sliding of said diagonal surfaces past each other when said rails are subject to elongation, said parallel planes being disposed at an angle of less than 45° to said plane including the longitudinal center line of the rail and said parallel planes being spaced apart a distance not exceeding one-eighth of an inch.
